UNITED STATES PATENT OFFICE.

GARTH G. GILPIN, OF RIVERSIDE, ILLINOIS.

RAILWAY-CAR-ROOF CONSTRUCTION.

Application filed March 13, 1925. Serial No. 15,382.

Reference is had to the accompanying drawings, which illustrate the preferred form of the invention, though it is to be understood that the invention is not limited to the exact details of construction shown and described, as it is obvious that various modifications thereof within the scope of the claims will occur to persons skilled in the art.

- 10 Rolled metallic Z bars are desirable as to compression members of the side trusses of steel frame railway box cars because of their great strength in any lateral direction and are also desirable as top chords of girders 15 because of their great strength (horizontally) to stiffen the girder against buckling. Such Z bars are positioned with the web horizontal and the oppositely projecting flanges positioned vertically.
- 20 It is customary to rivet additional members to the side plate which members are also riveted to the roof sheets. Such an arrangement unnecessarily increases the weight of the car as well as the cost and also 25 increases the time necessary to assemble the car and to repair it. Punching and riveting are expensive in time and money.

It is customary to attach the roofing sheets to the upstanding vertical flange of the Z 30 bar side plate so that the horizontal web of the side plate actually is a part of the roof of the car, because it is a covering for that part of the interior of the car between the outside sheathing and the lining, therefore, 35 such portion should be inclined or sloped to form a watershed and also to prevent the accumulation of cinders, dirt, etc., which would hold moisture and cause oxidation.

The line of impact of cars in coupling and 40 switching is through the couplers, considerably below the center of gravity of the car, therefore, the inertia of the car body tends to move it longitudinally when the car is suddenly stopped or its speed quickly decreased. This movement is real and causes 45 considerable damage by loosening the superstructure and the roof, etc. The inertia force of any weight in the car is in proportion to its vertical distance above the line of im-

pact (the coupler), therefore, any elimination of weight in the roof or side plate materially reduces the weaving stresses.

The sidewise swaying or swinging of the car when moving over an uneven track, crossings, switches, etc., increases or decreases 55 the angular relation of the roof to the side plate and has a tendency to distort or break the connection along this line.

The invention relates to a peculiar side plate for a railway house car having means 60 of attaching a car roof thereto and has for its objects the reduction in weight of the car; the reduction in the original as well as maintenance cost; a stronger and more rigid connection to resist the lateral weaving of 65 the car; to increase the bearing area of the roof sheets upon the side plate; to increase the tunnel clearance by decreasing the width of the car at the eaves and to put the roof sheet rivets in direct shear, and, furthermore, 70 to make a watershed of that part of the side plate forming part of the roof of the car.

In the drawings:

Fig. 1 shows my improved side plate 75 wherein the upper flange and sloping web are parallel and wherein the lower flange and vertical web are parallel.

Fig. 2 shows a construction wherein the slope of the lower web has been altered so 80 that it is not parallel to the upper flange and the plane of the vertical web has been altered to make the beam symmetrical.

Fig. 3 shows the relation of the upper flange to a carline and roof sheets of a rigid 85 type of roof.

Fig. 4 shows the relation of the upper flange to a carline and roof sheets of a flexible type of roof.

Fig. 5 shows a detail view of the rolled 90 section.

My particular form of side plate comprises two obtuse angled webs 1—2, one of which (1) is sloped to form a watershed and the other of which (2) is positioned substantially vertically. The sloping web is provided with an integral downwardly projecting flange 3 for attachment of the side

wall 4 of the car and the substantially vertical flange is provided with an integral flange for attachment of the roof framing elements and also the roof sheets, if desirable.

Figs. 1 and 2 show my side plate having the integral flange (7-8) at the upper part of the vertical web 2 projecting inwardly toward the car. When this flange projects inwardly the distance over the roof sheets is less, thereby not only saving in cost and weight of the car, but also in increasing the tunnel clearances, and minimizing the possible damage by side swiping.

Turning the upper flange inwardly has the further advantage that it forms a very simple rolling proposition. See Fig. 5.

In the construction shown in Fig. 1 the sloping web 2 and the upper projecting flange 7 are parallel, but in Fig. 2 these two members are positioned in convergent planes.

The relative position and lengths of the webs and flanges may be arranged to produce a symmetrical section, which is advantageous for simplicity of design and to avoid confusion in handling the member through the shop and applying it to the car. In Fig. 1 the webs 1 and 2 are of equal length and the flanges 3 and 7 are of equal length and the angular relation of each flange to its adjacent web is the same. The angular relation between web 1 and web 2 may vary and still produce a symmetrical section. In Fig. 31 the vertical web 2 and the vertical flange 3 are parallel, therefore, the upper flange 7 and the sloping web 1 must be parallel in order to produce a symmetrical section. The side plate shown in Fig. 1 is symmetrical about line A—A.

It may be desirable to increase the inclination of the sloping web 1 (in order to produce a greater watershed, or for some other reason). Such a construction is shown in Fig. 2. In order to maintain a symmetrical section the position of the substantially vertical web 2 has been altered until the angular relation of the flanges and their adjacent webs is the same. The side plate in Fig. 2 is symmetrical about line B—B.

My construction may be used with rigid steel roofs or flexible steel roofs. In a rigid steel roof the roof sheets and carlines (if any) are rigidly secured directly or indirectly to the side plate. Such a construction is shown in Figs. 1 and 3. Fig. 3 is a section on line 7—7 in Fig. 1 and shows the relation between the carline 10, the roof sheets 11 and the side plate.

In a flexible roof the carlines 20 are rigidly secured to the side plate and the roof sheets are usually supported loosely by the side plates (and perhaps other frame members) and some sort of freely flexible water-proof arrangement is used between the edges

of the roof sheets 21 and the carline. A typical construction is shown in Fig. 4, which is a section along line 8—8 of Fig. 2.

It is understood that a flexible or a rigid roof may be used with any construction within this disclosure and still come within the scope of the invention.

I claim:

1. A railway car frame member comprising two obtuse angled webs, an integral flange at the upper part of one web, and an integral flange at the lower part of the last mentioned web, the relative position and lengths of the webs and flanges producing a symmetrical member. 80

2. A railway car frame member comprising two obtuse angled webs, an integral flange at the upper part of one web parallel to the other web, and an integral flange at the lower part of the last mentioned web parallel to the first mentioned web, the relative position and lengths of the webs and flanges producing a symmetrical member. 85

3. A railway car side plate comprising two obtuse angled webs, and a flange at the outer end of each of said webs projecting from the opposite side of said web than the other of said webs. 90

4. In a railway car comprising a roof, a side wall, and a side plate; said side plate having two obtuse angled webs, an inwardly extending flange at the upper part of one web to which the roof is secured, and an integral flange at the lower part of the other web to which the side wall is secured. 95

5. In a railway car comprising a roof, a side wall, and a side plate; said side plate having two obtuse angled webs, an inwardly extending flange at the upper part of one web to which the roof is secured, and an integral flange at the lower part of the other web parallel to the first mentioned web to which the side wall is secured. 105

6. In a railway car having a side plate comprising a substantially vertical web with a flange at its upper part projecting inwardly and upwardly therefrom and a downwardly and outwardly inclined web with a downwardly projecting flange at its lower part; the combination of a roof overlying said inwardly projecting flange and provided with a vertical extension adjacent said vertical web, and a side wall positioned on the inside of said downwardly projecting flange. 110

7. In a railway car, the combination of a side plate comprising two obtuse angled webs, and a flange at the outer end of each of said webs with the relative position and length of the webs and flanges forming a symmetrical member, a roof sheet overlying the upper of said flanges, and a side wall positioned on the inside of the lower of said flanges. 120

8. A railway car frame member comprising

ing two obtuse angled webs, a flange at the outer end of one of said webs projecting from the opposite side thereof than the other of said webs, and a flange at the outer end 5 of said other web projecting from the opposite side thereof than the first mentioned web.

9. A railway car frame member comprising two obtuse angled webs, a flange at the

outer end of one of said webs projecting 10 from the opposite side thereof than the other of said webs, said flange being parallel to said other web, and a flange at the outer end of said other web projecting from the opposite side thereof than the first mentioned web. 15
